UNITED STATES PATENT OFFICE.

CHARLES A. ALDEN, OF STEELTON, PENNSYLVANIA.

RAILROAD-SWITCH STAND.

1,099,231.

Specification of Letters Patent.

Patented June 9, 1914.

Application filed April 29, 1913. Serial No. 764,304.

To all whom it may concern:

Be it known that I, CHARLES A. ALDEN, a citizen of the United States, residing at Steelton, in the county of Dauphin and State of Pennsylvania, have invented certain new and useful Improvements in Railroad-Switch Stands, of which the following is a specification.

This invention relates to railroad switch stands wherein mechanism is provided to move a switch to either of its two set positions and wherein mechanism is provided to move a signal to either of two set positions to indicate the position of the switch. In switch stands of this character, it has been the practice to provide mechanism to move the signal at the same time that the switch is moved, so that if the switch stops short of its complete movement to one of its set positions, the signal will correspondingly stop short of its complete movement to one of its set positions, and yet be near enough to it to deceive the persons concerned into the belief that the switch is properly set. This is objectionable, for the reason that, as is well known, many accidents and much damage have resulted from improperly set switches.

The object of my invention is to overcome this objection by providing a switch stand which shall be simple in construction and efficient in operation and which shall be provided with means whereby, when the switch stand is operated, the signal shall be moved to a definite position intermediate its two set positions, before the switch is moved from one set position to the other, and whereby, the signal shall thereafter be moved from the intermediate position to its set position indicating the set position to which the switch was moved, so that in all positions of the switch between its two set positions, the signal will occupy the definite intermediate position, indicating that the switch is in neither one nor the other of its two set positions.

With this object in view the precise nature of the invention will be hereinafter fully described and particularly claimed.

In the accompanying drawings, illustrating my invention, Figure 1, is a plan of a switch stand, embodying my invention. Fig. 2, is a vertical section through the switch stand, taken on line 2—2 through the lower

portion of the stand and on line 2—2 through the upper portion of the stand. 55 Fig. 3, is a vertical section, similar to the upper portion of Fig. 2, but showing certain parts in different positions. Fig. 4, is a horizontal section through the switch stand, on line 4—4 of Fig. 2. Fig. 5, is a 60 view of the lower portion of a vertically movable sleeve for operating the signal shaft, showing the diverging ribs thereon. Fig. 6, is a view of a portion of the signal shaft and the collar carried thereby showing the diverging grooves in the collar adapted to coöperate with the ribs on the sleeve shown in Fig. 5. Figs. 7, 8 and 9 are 65 top views of the coöperating sleeve and collar shown in Figs. 5 and 6, respectively, 70 showing the positions thereof when the stand is in one set position, in the intermediate position and in the other set position, respectively. Figs. 10, 11 and 12, are horizontal sections through the switch and signal shafts and the lower portion of the sleeve shown in Fig. 5, showing the head on the lower end of the sleeve and the part on the signal shaft with which the head coöperates to hold the signal shaft in the intermediate position, the parts being shown in the three positions corresponding with the positions of the parts shown in Figs. 7, 8 and 9, respectively.

Referring to the drawings, 3 designates a 85 vertically-extending hollow frame or casing having horizontal partition walls 5 and 6 and horizontal base portions 7 adapted to be secured to the cross ties of a railroad adjacent a switch. Extending centrally through 90 the frame 3 is the vertical switch operating shaft 8 which is mounted to turn in bearings in the walls 5 and 6 and which is provided on its lower end with a crank 9 connected to the switch operating rod 10 which is adapted 95 to operate the switch when the shaft 8 is turned in the usual manner. The upper portion of the shaft 8 has a reduced portion 11 which extends through a central boss 12 formed on a head 13 and the upper end of 100 the shaft 8 is still further reduced and threaded for the reception of a nut 14 which secures the boss 12 or head 13 to the shaft 8. The portion 11 of the shaft is made substantially square in cross section and it is fitted 105 to a similarly shaped opening in the boss 12

so that the shaft 8 and the head 13 may be locked together to turn as a unit. The head 13 is made hollow and it closes the top of the frame or casing 3, and the lower portion of the head 13 embraces and is rotatably engaged with the top of the casing 3 which is made concentric with the shaft, thus strengthening the parts by giving the shaft 8 and head 13 an additional bearing on the top of the frame 3. Pivoted to one side of the head 13, at 15, is a lever 16, the outer end of which is adapted to be grasped by hand to operate the switch and signal, as will be hereinafter explained. The lever 16 extends through a slot in the side wall of the head 13, and the inner end 17 of the lever is bifurcated and embraces the shaft 8 and a sleeve 18 which surrounds the shaft and is slidable vertically thereon. The end 17 of the lever 16 is slotted, at 19, to receive the ends of a pin 20 which extends transversely through the shaft 8 and sleeve 18, the pin 20 being carried by the sleeve 18 and fitted to a vertical slot 21 in the shaft 8, so that the lever 16 may be moved on its pivot 15 from the position shown in Fig. 2 to the position shown in Fig. 3 and back again.

When the lever 16 is in the raised position shown in Fig. 3, it may be operated to turn the shaft 8, in either direction, a quarter revolution, to move the switch connected to the rod 10 to either of its two set positions, and the top of the frame 3 is provided with two notches 22 properly spaced and located to receive the lever 16 when it is lowered into the position shown in Fig. 2, one notch 22 receiving the lever, after the switch has been moved to one set position, and the other notch 22 receiving the lever 40 after the switch is moved to the other set position, and the notches 22 serving to lock the shaft 8 against rotation and prevent accidental displacement of the switch from either of its set positions.

The frame 3 is provided below each notch 22 with a loop 23 which extends through an opening in the lever 16 when the same is down, as shown in Fig. 2, and the outer end of the loop 23 is adapted to receive a locking device to lock the lever against being raised.

Arranged laterally adjacent and parallel to the switch operating shaft 8 is the signal operating shaft or target mast 24, the lower portion of which is mounted to turn in a bearing in the wall 5 and a bearing shaft 24 extends up through the head 13 and through a slot 26 in the top wall of the head, and the shaft 24 extends some distance above the head 13 and is adapted to carry the usual target or signal which is to indicate the position of the switch. The slot 26 permits the switch operating shaft 8 and head 13 to be turned a quarter revolution with respect to the signal operating shaft 24 in setting the switch, and the slot 26 is covered by a guard

plate 27 which rests upon the head 13. This guard plate 27 surrounds and is pivoted on the boss 12 and the plate also surrounds and engages the shaft 24, so that when the head 13 is turned, the plate 27 will be prevented from turning therewith by the shaft 24. It will thus be seen that the plate 27 will close the top of the slot 26 and guard the same in all positions of the head 13.

The signal operating shaft 24 is controlled and actuated by the sleeve 18 hereinbefore referred to. Formed on the lower portion of this sleeve 18 are two upwardly diverging spiral ribs 28 which are adapted to co-operate, one with one and one with the other of two upwardly diverging spiral grooves 29 formed in a collar 30 which is secured to the signal operating shaft 24, as shown. The ribs 28 and the grooves 29 are located with respect to each other so that when the lever 16 is down and the sleeve 18 is raised, one of the ribs 28 will be in one of the grooves 29, and that when the lever 16 is raised and the sleeve 18 is down, the ribs 28 will be below the grooves 29 and the sleeve 18 will be free to turn independently of the shaft 24; and the ribs 28 and grooves 29 are formed and related to each other so that when the sleeve 18 is lowered, turned and then raised, the ribs and grooves will co-operate to turn the collar 30 and shaft 24 a quarter revolution, moving the signal from one set position, indicating one set position of the switch to another set position, indicating the other set position of the switch; that is to say, when the sleeve 18 is lowered, the rib 28 engaged with its groove 29 in the collar 30 will first turn the shaft 24 one-eighth of a revolution and then leave its groove 29 in the position shown in Fig. 8; when the sleeve 18 is then turned one-quarter of a revolution, the upper end of the other rib 28 will be brought into registry with the bottom of its groove 29 in the collar 30; and when the sleeve 18 is then raised, said other rib will enter its groove 29 and continue the turning of the shaft 24 another one-eighth of a revolution. Thus it will be seen that the lowering of the sleeve 18 will turn the signal operating shaft 24 from one set position to an intermediate position midway between its two set positions, indicating the two set positions of the switch; that the turning of the sleeve 18, when the shaft 24 is turned to move the switch from one to the other of its set positions, will not disturb the signal in its intermediate position; and that the raising of the sleeve 18, after the setting of the switch, will continue the turning of the shaft 24 to move the signal to its set position indicating the set position to which the switch was previously moved.

In order to hold the signal operating shaft 24 in the intermediate position while the sleeve 18 is down and during the turning

thereof with the shaft 8 to move the switch from one to the other of its set positions, I provide the following: Secured to or formed on the bottom of the sleeve 18 is a round head 31 having a beveled periphery, as shown, which is adapted to enter a socket 32 in a collar 33 which is secured to the shaft 24, the wall of the socket 32 being beveled to correspond with the head 31. When the sleeve 18 is lowered, the socket 32 is brought into alinement with the head 31, as shown in Fig. 11, and, as the sleeve 18 completes its downward movement, the head 31 enters the socket 32 and engages the wall thereof and holds the collar 33 and shaft 24 in the intermediate position while the sleeve 18 is turned. During the initial upward movement of the sleeve 18, the head 31 leaves the socket 32, permitting the head 33 and shaft 24 to be turned during the continued upward movement of the sleeve 18. By making the head 31 beveled, it may start to enter the socket 32 before the shaft 24 completes its movement to the intermediate position, thereby preventing the parts from being accidentally moved out of working relationship.

The operation of the parts briefly described is as follows: When the parts are in the positions shown in Figs. 1, 2, 4, 7 and 10, the switch shaft is held in one of its two set positions by the lever 16 engaging one of the notches 22, and the signal shaft 24 is held in one of its two set positions to hold the signal in position indicating the position of the switch, by one of the ribs 28 engaging the walls of one of the grooves 29. When it is desired to move the switch operating shaft to its other set position, the hand lever 16 is moved from one notch 22 to the other notch 22 by first raising the lever 16 to the position shown in Fig. 3, then moving the lever horizontally from its position above the notch 22 from which it was raised to a position above the other notch 22 and then lowering the lever 16 into said other notch. The raising of the lever 16 lowers the sleeve 18 and turns the signal operating shaft 24 to the intermediate position and moves the head 31 into the socket 32, the horizontal movement of the lever 16 turns the shaft 8 a quarter revolution from one to the other of its set positions, while the head 31, turning in the socket 32 holds the signal operating shaft 24 in the intermediate position, as shown in Figs. 8 and 11, and the lowering of the lever 16 raises the sleeve 18 and thereby continues the turning of the signal operating shaft 24 to the set position indicating the set position to which the switch operating shaft was previously moved. This same operation takes place in moving the lever 16 from either one of the notches 22 to the other in moving the switch from one set position to the other, the parts working in one direction when the lever 16 is moved in one direction

to move the switch to one position and the parts working in the reverse direction when the lever 16 is moved in a reverse direction to move the switch to the other position.

I claim:

1. In a switch stand, the combination of a frame, a switch operating shaft movable to two set positions, a signal operating shaft movable to two set positions, and means operative to move the signal operating shaft from one of its set positions to an intermediate position and move the switch operating shaft from one to the other of its set positions and thereafter move the signal operating shaft from said intermediate position to the other of its set positions. 70

2. In a switch stand, the combination of a frame, a switch operating shaft movable to two set positions, a signal operating shaft movable to two set positions, an operating arm for said shafts, said arm being movable to two set positions, and means operated by said arm, in moving from one to the other of its set positions, to move the signal operating shaft from one of its set positions to an intermediate position and move the switch operating shaft from one to the other of its set positions and thereafter move the signal operating shaft from said intermediate position to the other of its set positions. 85

3. In a switch stand, the combination of a frame, a switch operating shaft movable to two set positions, a signal operating shaft movable to two set positions, an operating arm for said shafts, said arm being movable to two set positions, and means operated by said arm, in moving from one to the other of its set positions, to move the signal operating shaft from one of its set positions to an intermediate position, and hold the signal operating shaft in said intermediate position and move the switch operating shaft from one to the other of its set positions, and thereafter move the signal operating shaft from said intermediate position to the other of its set positions. 95

4. In a switch stand, the combination of a frame, a switch operating shaft movable to two set positions, a signal operating shaft movable to two set positions, an operating arm for said shafts, said arm being movable to two set positions and adapted to be first raised and then moved horizontally and then lowered, in moving from one to the other of its set positions, and means operated by the raising of said arm to move the signal operating shaft from one of its set positions to an intermediate position and operated by the lowering of said arm to move the signal operating shaft from said intermediate position to the other of its set positions and operated by the horizontal movement of said arm to move the switch operating shaft from one to the other of its set positions. 115

5. In a switch stand, the combination of a 120

125

130

frame, a switch operating shaft movable to two set positions, a signal operating shaft movable to two set positions, an operating arm for said shafts, said arm being movable 5 to two set positions and adapted to be first raised and then moved horizontally and then lowered, in moving from one to the other of its set positions, means operated by the raising of said arm to move the signal operating shaft from one of its set positions to an intermediate position and operated by the lowering of said arm to move the signal operating shaft from said intermediate position to the other of its set positions, means operated 10 by the horizontal movement of said arm to move the signal operating shaft from one to the other of its set positions, and means operated by said arm to hold the signal operating shaft in said intermediate position during 15 the horizontal movement of said arm.

6. In a switch stand, the combination of a frame, a switch operating shaft adapted to be turned to two set positions, a signal operating shaft adapted to be turned to two 25 set positions, a sleeve slidable on the switch operating shaft, means operative to turn said sleeve and move it up and down on said shaft, and means operated by both the up and down movements of said sleeve for 30 turning the signal operating shaft in one direction.

7. In a switch stand, the combination of a frame, a switch operating shaft adapted to be turned to two set positions, a signal 35 operating shaft adapted to be turned to two set positions, a sleeve slidable on the switch operating shaft and adapted to turn about the axis thereof and having two diverging spiral ribs thereon, means operative to turn 40 said sleeve and move it longitudinally in two directions, and a part fixed to the signal operating shaft and having two diverging spiral grooves therein, one groove being adapted to receive and coöperate with one 45 rib and turn the signal operating shaft when said sleeve is moved in one direction, the other groove being adapted to receive and coöperate with the other rib and turn the signal operating shaft when said sleeve is 50 moved in the reverse direction, and said ribs being brought into operative relation with said grooves, respectively, when said sleeve is turned.

8. In a switch stand, the combination of 55 a frame, a switch operating shaft adapted to be turned to two set positions, a signal operating shaft adapted to be turned to two set positions, a sleeve slidable on the switch operating shaft and adapted to turn therewith about the axis thereof and having two diverging spiral ribs thereon, means operative to turn the switch operating shaft and to move said sleeve longitudinally thereon in two directions, and a part fixed to the 60 signal operating shaft and having two di-

verging spiral grooves therein, one groove being adapted to receive and coöperate with one rib and turn the signal operating shaft when said sleeve is moved in one direction, the other groove being adapted to receive and coöperate with the other rib and turn the signal operating shaft when said sleeve is moved in the reverse direction, and said ribs being brought into operative relation with said grooves, respectively, when said 70 sleeve is turned.

9. In a switch stand, the combination of a frame, a switch operating shaft adapted to be turned to two set positions, a signal operating shaft adapted to be turned to two 80 set positions, a sleeve slidable on the switch operating shaft and adapted to turn therewith about the axis thereof and having two diverging spiral ribs thereon, means operative to turn the switch operating shaft and to move said sleeve longitudinally thereon in two directions, a part fixed to the signal operating shaft and having two diverging spiral grooves therein, one groove being adapted to receive and coöperate with one 85 rib and turn the signal operating shaft when said sleeve is moved in one direction, the other groove being adapted to receive and coöperate with the other rib and turn the signal operating shaft when said sleeve is 90 moved in the reverse direction, and said ribs being brought into operative relation with said grooves, respectively, when said sleeve is turned, and means to prevent the 95 turning of the signal operating shaft during the turning of the switch operating shaft.

10. In a switch stand, the combination of a frame, a switch operating shaft adapted to be turned to two set positions, a signal 105 operating shaft adapted to be turned to two set positions, a sleeve slidable on the switch operating shaft and adapted to turn therewith about the axis thereof and having two diverging spiral ribs thereon, means operative to turn the switch operating shaft and to move said sleeve longitudinally thereon in two directions, a part fixed to the signal operating shaft and having two diverging spiral grooves therein, one groove being adapted to receive and coöperate with one rib and turn the signal operating shaft when said sleeve is moved in one direction, the other groove being adapted to receive and coöperate with the other rib and turn the signal operating shaft when said sleeve is 110 moved in the reverse direction, and said ribs being brought into operative relation with said grooves, respectively, when said sleeve is turned, and means to prevent the 115 turning of the signal operating shaft during the turning of the switch operating shaft, the last named means comprising a part fixed to the signal operating shaft and having a socket therein and a head carried 120

by said sleeve and movable therewith into and from said socket.

11. In a switch stand, the combination of a frame, a switch operating shaft adapted to be turned to two set positions, a signal operating shaft laterally adjacent and parallel to the switch operating shaft and adapted to be turned to two set positions, a sleeve slideable on the switch operating shaft and having a spiral rib thereon, means operative to move said sleeve longitudinally on the switch operating shaft, and a part fixed to the signal operating shaft and having a spiral groove therein adapted to receive and co-operate with said rib and turn the signal operating shaft when said sleeve is moved longitudinally.

12. In a switch stand, the combination of a frame, a switch operating shaft adapted to be turned to two set positions, a signal operating shaft laterally adjacent and parallel to the switch operating shaft and adapted to be turned to two set positions, a sleeve slideable on the switch operating shaft and adapted to turn about the axis thereof and having a spiral rib thereon, means operative to turn the switch operating shaft and to move said sleeve longitudinally thereon, a part fixed to the signal operating shaft and having a spiral groove therein adapted to receive and co-operate with said rib and turn the signal operating shaft when said sleeve is moved longitudinally, and means to prevent the turning of the signal operating shaft during the turning of the switch operating shaft.

13. In a switch stand, the combination of a frame, a switch operating shaft adapted to be turned to two set positions, a signal operating shaft laterally adjacent and parallel to the switch operating shaft and adapted to be turned to two set positions, a sleeve slideable on the switch operating shaft and adapted to turn about the axis thereof and having a spiral rib thereon, means operative to turn the switch operating shaft and to move said sleeve longitudinally thereon, a part fixed to the signal operating shaft and having a spiral groove therein adapted to receive and co-operate with said rib and turn the signal operating shaft when said sleeve is moved longitudinally, and means to prevent the turning of the signal operating shaft during the turning of the switch operating shaft, the last named means comprising a part fixed to the signal operating shaft and having a socket therein and a head carried by said sleeve and movable therewith into and from said socket.

14. In a switch stand, the combination of a frame, a switch operating shaft adapted to be turned to two set positions, a signal operating shaft laterally adjacent and parallel to the switch operating shaft and adapted to be turned to two set positions, a

head fixed to the switch operating shaft, an arm pivoted to said head and movable to two set positions, a sleeve slideable longitudinally on the switch operating shaft and connected to said arm, said arm being adapted to turn said head and the switch operating shaft and to move said sleeve longitudinally when moved from one to the other of its set positions, and means operated by the longitudinal movement of said sleeve to turn the signal operating shaft.

15. In a switch stand, the combination of a frame, a switch operating shaft adapted to be turned to two set positions, a signal operating shaft laterally adjacent and parallel to the switch operating shaft and adapted to be turned to two set positions, a head fixed to the switch operating shaft, an arm pivoted to said head and movable to two set positions, a sleeve slideable longitudinally on the switch operating shaft and connected to said arm, said arm being adapted to turn said head and the switch operating shaft and to move said sleeve longitudinally when moved from one to the other of its set positions, means operated by the longitudinal movement of said sleeve to turn the signal operating shaft, and means to prevent the turning of the signal operating shaft during the turning of the switch operating shaft.

16. In a switch stand, the combination of a frame, a switch operating shaft adapted to be turned to two set positions, a signal operating shaft adapted to be turned to two set positions, a head fixed to the switch operating shaft, an arm pivoted to said head and movable to two set positions, a sleeve slideable longitudinally on the switch operating shaft and connected to said arm, said arm being adapted to turn said head and the switch operating shaft and to move said sleeve up and down in moving from one to the other of its set positions, and means operated by both up and down movements of said sleeve to turn the signal operating shaft in one direction.

17. In a switch stand, the combination of a frame, a switch operating shaft adapted to be turned to two set positions, a signal operating shaft adapted to be turned to two set positions, a head fixed to the switch operating shaft, an arm pivoted to said head and movable to two set positions, a sleeve slideable longitudinally on the switch operating shaft and connected to said arm, said arm being adapted to turn said head and the switch operating shaft and to move said sleeve up and down in moving from one to the other of its set positions, and means operated by both up and down movements of said sleeve to turn the signal operating shaft in one direction, and means to prevent the turning of the signal operating shaft during the turning of the switch operating shaft.

18. In a switch stand, the combination of

- 6
1. In a switch stand, the combination of a frame, a switch operating shaft adapted to be turned to two set positions, a signal operating shaft adapted to be turned to two set positions, a head fixed to the switch operating shaft, an arm pivoted to said head and movable to two set positions, a sleeve slidable longitudinally on the switch operating shaft and connected to said arm, said arm being adapted to turn said head and the switch operating shaft and to move said sleeve up and down in moving from one to the other of its set position, means operated by both up and down movements of said sleeve to turn the signal operating shaft in one direction, and means to prevent the turning of the signal operating shaft during the turning of the switch operating shaft, the last named means comprising a part fixed to the signal operating shaft and having a socket therein and a head carried by said sleeve and movable therewith into and from said socket.
2. In a switch stand, the combination of a frame, a switch operating shaft adapted to be turned to two set positions, a signal operating shaft adapted to be turned to two set positions, a sleeve slidable longitudinally on the switch operating shaft, an arm pivoted to said head and movable to two set positions and having a bifurcated end embracing said sleeve, a pin extending through a slot in the switch operating shaft and into slots in the bifurcated end of said arm, said arm being adapted to turn said head and the switch operating shaft and to move said sleeve longitudinally when moved from one to the other of its set positions, and means operated by the longitudinal movement of said sleeve to turn the signal operating shaft.
3. In a switch stand, the combination of a frame, a switch operating shaft adapted to be turned to two set positions, a signal operating shaft adapted to be turned to two set positions, means operative to move the switch operating shaft from one to the other of its set positions and to move the signal operating shaft from one of its set positions to an intermediate position and from the intermediate position to its other set position, and means to hold the signal operating shaft in said intermediate position while the switch operating shaft is being moved.
4. In a switch stand, the combination of a frame, a switch operating shaft adapted to be turned to two set positions, a signal operating shaft adapted to be turned to two set positions, means operative to move the switch operating shaft from one to the other of its set positions and to move the signal operating shaft from one of its set positions to an intermediate position and from the intermediate position to its other set position, means to hold the signal operating shaft in said intermediate position while the switch operating shaft is being moved.
5. In a switch stand, the combination of a frame, a switch operating shaft adapted to be turned to two set positions, a signal operating shaft adapted to be turned to two set positions, a head fixed to the switch operating shaft, an arm pivoted to said head and movable to two set positions, a sleeve slidable longitudinally on the switch operating shaft and connected to said arm, said arm being adapted to turn said head and the switch operating shaft and to move said sleeve up and down in moving from one to the other of its set position, means operated by both up and down movements of said sleeve to turn the signal operating shaft in one direction, and means to prevent the turning of the signal operating shaft during the turning of the switch operating shaft, the last named means comprising a part fixed to the signal operating shaft and having a socket therein and a head carried by said sleeve and movable therewith into and from said socket.

6. In a switch stand, the combination of a frame, a switch operating shaft mounted to turn in said frame to two set positions, a signal operating shaft laterally adjacent and parallel to the switch operating shaft and mounted to turn in said frame to two set positions, a head fixed to the switch operating shaft, and means operative to turn said head and the switch operating shaft from one to the other of its set positions and to turn the signal operating shaft from one to the other of its set positions, said signal operating shaft extending through a slot in said head.

7. In a switch stand, the combination of a frame, a switch operating shaft mounted to turn in said frame to two set positions, a signal operating shaft laterally adjacent and parallel to the switch operating shaft and mounted to turn in said frame to two set positions, a head fixed to the switch operating shaft, and means operative to turn said head and the switch operating shaft from one to the other of its set positions and to turn the signal operating shaft from one to the other of its set positions, said signal operating shaft extending through a slot in said head.

8. In a switch stand, the combination of a frame, a switch operating shaft mounted to turn in said frame to two set positions, a signal operating shaft laterally adjacent and parallel to the switch operating shaft and mounted to turn in said frame to two set positions, a head fixed to the switch operating shaft, means operative to turn said head and the switch operating shaft from one to the other of its set positions and to turn the signal operating shaft from one to the other of its set positions, said signal operating shaft extending through a slot in said head, and a guard plate covering said slot and connected to the signal operating shaft.

9. In a switch stand, the combination of a frame, a switch operating shaft mounted to turn in said frame to two set positions, a signal operating shaft laterally adjacent and parallel to the switch operating shaft and mounted to turn in said frame to two set positions, a head fixed to the switch operating shaft, means operative to turn said head and the switch operating shaft from one to the other of its set positions and to turn the signal operating shaft from one to the other of its set positions, said signal operating shaft extending through a slot in said head, and a guard plate covering said slot and pivoted on the turning axis of said head and prevented from turning about said axis by engagement with the signal operating shaft.

10. In a switch stand, the combination of a frame, a switch operating shaft mounted to turn in said frame to two set positions, a signal operating shaft laterally adjacent and parallel to the switch operating shaft and mounted to turn in said frame to two set positions, a head fixed to the switch operating shaft and fitted to a bearing on said frame to turn about the axis of the switch.

operating shaft, and means operative to turn said head and the switch operating shaft from one to the other of its set positions and to turn the signal operating shaft from one to the other of its set positions, said signal operating shaft extending through a slot in said head.

In testimony whereof I affix my signature in presence of two witnesses.

CHARLES A. ALDEN.
